UNITED STATES PATENT OFFICE.

BENJAMIN LONG, OF CHAMPAIGN, ILLINOIS.

PAPER RECEPTACLE.

1,181,781.

Specification of Letters Patent.

Patented May 2, 1916.

Application filed November 12, 1914. Serial No. 871,720.

To all whom it may concern:

Be it known that I, BENJAMIN LONG, a citizen of the United States of America, residing at Champaign, in the county of 5 Champaign and State of Illinois, have invented certain new and useful Improvements in Paper Receptacles, of which the following is a specification.

This invention relates to improvements in 10 paper receptacles, more especially of the carton type.

The invention has for its object, among 15 other things, to provide for the disposition or reception of waste paper, particularly as called for in barber shops, while it may be utilized by dentists, manicurists, etc., for that purpose.

A further object is to provide for more 20 sanitary measures and cleanliness along the aforesaid lines.

A still further object is to provide suitable 25 facilities in connection with such receptacles or cartons for advertising purposes.

The invention therefore consists of a receptacle or carton, the structure of which 30 has certain peculiarities as to the formation and arrangement of the parts thereof, substantially as hereinafter more fully disclosed and defined by the appended claims.

35 In the accompanying drawing is illustrated the preferred embodiment of my invention, wherein it will be understood that various changes and modifications may be made as to the detailed construction and arrangement of parts without departing from the scope of the claims, and in which drawing:

Figure 1 is a perspective view of my carton or receptacle. Fig. 2 is a plan view of 40 the blank from which the carton is made.

In carrying out my invention, I form 45 preferably from paper a blank as disclosed in Fig. 2 designated as 1, in which it will be seen that a carton 2 is the resultant thereof, as illustrated in Fig. 1.

The receptacle or carton 2 has its bottom and several sides, designated as 3 and 4, respectively, formed in a continuous piece. The bottom 3, it will be noted, is in continuation of one side of the receptacle and has 50 its other or free edges formed with flaps 5, 6 and 7, respectively, which are caused to overlap and suitably secured or pasted to the corresponding body portions of the box, thus forming a closure for the otherwise open 55 lower end of the body, in other words consti-

tuting the bottom of the receptacle. The body of the receptacle is suitably creased so as to form its sides, one edge thereof being formed with a flap 8, the same overlapping and being pasted or otherwise secured along the opposite edge of the body. The upper edges of the sides of said body of the receptacle are formed with flaps, 9, 10, 11 and 12, respectively, which flaps are formed at their ends on diagonal lines, and which ends meet or overlap each other and may be folded down, and thus held together, thus providing for contracting the top or open end of the receptacle, as seen in Fig. 1 for the suitable retention of the contents of the receptacle, or to that extent which would only be necessary in holding waste paper for instance, as used by barbers, manicurists, dentists, etc., all of which will be readily appreciated, the box and its contents all thus being adapted to be readily disposed of by incineration or otherwise, as will be readily understood. From this it will be gathered that a receptacle or carton for the purpose indicated is thus cheaply gotten up, as is apparently an object, and which is a desideratum.

It is also remarked that my receptacle or carton may serve as a medium for advertising purposes, by printing business matter, etc., thereon the same thus being conspicuously brought to attention in public places, especially of the character as above indicated, said receptacle with its advertising matter being prominently displayed to the view of patrons of such places. It is also observed that the receptacle may be gotten up in any fanciful or configurative outline, which would have the effect, it is obvious, of 95 more or less attracting attention, and thus add to the utility of the device, particularly as an advertising agent.

I claim--

1. A paper receptacle of the character specified formed from a single blank and comprising side members, the meeting edges of which are united by a flap and a bottom member formed by an extension of one of the intermediate side members of the blank, the free edges of the bottom member having flaps adapted to be folded in and united or secured to the bottom edges of the other side members of the receptacle, the upper edges of the side members having inwardly extending overhanging flaps which extend entirely around the upper edge of the recep-

tacle and form a partial freely yieldable closure for the top thereof.

2. A paper receptacle of the character specified formed from a single blank and 5 comprising side members, the meeting edges of which are united by a flap and a bottom member formed by an extension of one of the intermediate side members of the blank, the upper edges of the side members having 10 inwardly extending flaps which extend en-

tirely around the upper edge of the receptacle and form a partial yieldable closure for the top thereof.

In testimony whereof I affix my signature in presence of two witnesses.

BENJAMIN LONG.
